UNITED STATES PATENT OFFICE.

LUIS CILLER, OF EUREKA, UTAH.

ELECTRIC FAN.

Application filed March 10, 1925. Serial No. 14,492.

This invention relates to electric fans and pertains particularly to an electric fan of novel construction.

The primary object of this invention is 5 the provision, in a manner as hereinafter set forth, of an electric fan preferably of the type adapted to be suspended from the ceiling, constructed in imitation of an air vessel and designed to revolve, while at the 10 same time causing air currents to be directed horizontally and downwardly therefrom.

The invention contemplates the provision 15 of a miniature airplane and a suspension rod adapted to have one end fixed to the ceiling and extending through the body of the plane upon the longitudinal center thereof, and secured at the lower end against the underside of the body in such a 20 way that the body will be capable of revolution about the suspension bar. The plane is provided with vertical and horizontal tail rudders, the vertical rudder being set at an angle so that air currents created by a 25 fan mounted upon an electric motor positioned upon the forward part of the fuselage of the plane, will strike the rudder and cause the plane to revolve upon a support. The wings of the plane are provided with 30 air deflecting means whereby the air currents set up by the fan at the forward end of the plane will be partly deflected downwardly from the body of the plane.

A further and final object of this invention is the provision, in a manner as hereinafter set forth, of an electric fan comprising 35 an airplane in miniature, having a light means thereon and designed to be attractive in appearance and efficient in operation.

40 The invention will be best understood from a consideration of the following detailed description taken in connection with the accompanying drawing forming a part of this specification, with the understanding 45 that the invention is not confined to any strict conformity with the showing of the drawing, but may be changed and modified so long as such changes and modifications mark no material departure from the salient features of the invention as expressed in 50 the appended claims.

In the drawings:—

Fig. 1 is a side elevation of the fan structure embodying this invention.

55 Fig. 2 is a top plan view of the same.

Fig. 3 is a front elevation of the same.

Fig. 4 is the horizontal section between the wings of the plane looking up toward the underside of the top wing.

Fig. 5 is a section taken upon the line 5—5 of Fig. 1.

Referring now to the drawings in detail wherein like numerals of reference indicates corresponding parts throughout the several views, the device embodying this invention comprises a miniature airplane having the fuselage 1. Extending across the forward portion of the fuselage 1 is a pair of spaced superposed top and bottom wings 2 and 3 respectively, held in spaced 65 relation by the vertical standards 4. The lower wing 3 extends beneath the fuselage 1 and the fuselage is terminated adjacent the front edges of the wings, and has extending from its lower portion the platform 70 or extension 5. At the rear of the fuselage there is placed vertical and horizontal steering rudders 6 and 7 respectively, the rudder 6 being in two portions, the portion 8 thereof being secured at an obtuse angle 75 to and with respect to the portions 6 by means of the angle brackets 9.

Secured to the underside of the plane are a pair of depending arms 10 carrying there between an axle 11 on which a pair of 80 wheels 12 are supported to complete the representation of the airplane.

Adjacent the rear edge of the upper and lower planes 2 and 3 upon each side of the fuselage, a section is cut out of the plane 90 and held at an angle with respect to the adjacent wing to set up air deflecting members. The members 13 which are cut from the upper wing 2 extend downwardly and rearwardly as indicated in Figure 1 and are 95 held in this downwardly angled position by the brackets 14. The lower members 15 extend upwardly and inwardly above the lower wing 3 as shown in Figure 1, and are held in this upward extending position by 100 the members or brackets 16. The lower members 15 are thus supported at an angle above openings 17 in the lower wing of the plane.

105 Mounted upon the extension or platform 5 at the front end is the electric motor 18 having the usual shaft 19, which shaft extends longitudinally of the body of the plane, and has fixed thereon the propeller or fan blades 20.

110 Although this plane might be supported in any suitable manner by a suspension bar

- 21, the upper end 22 of which is adapted to be secured to a ceiling, and the lower portion of the suspension rod extends through the longitudinal center of the wings and fuselage and extends beyond the underneath side thereof and has threaded upon its lower ends beneath the fuselage the portion 23 of a ball race member. This ball race member 23 carries a series of friction balls 24 in an annular groove formed in the upper face thereof and these friction balls work in a corresponding annular groove formed in the underface of a corresponding ball race member 25 which member 25 is fixed by means of the bolts 26 to the underside of the plane fuselage. The plane is thus directly supported upon the ball members 24 and 23 which is secured to the lower end of the suspension rod 21, to revolve thereabout.
- 20 The suspension rod 22 is hollow as shown in Fig. 5 and has passed therethrough an electrical conducting element 27 which extends through an aperture 28 in the rod 21 into the interior of the fuselage 1 to, feed current to the motor 18 through the following means.
- The rod 21, within the fuselage 1 has secured thereabout the annular current distributing members 29 and 30 respectively.
- 20 The upper member 29 has a binding post 31 thereon to which one of the current bearing conductors is secured. The member 3 also has thereon a binding post 32 to which the other electrical conductor is attached.
- 35 Secured to one inner side of the body 1 is a pair of contact brush fingers 33 and 34 respectively, the brush 33 bearing or rubbing against the annular distributor 29 and the brush 34 bearing against the distributor 30. Binding posts 35 are mounted at the fixed end of the brushes 33 and 34 and to these binding posts the ends of electrical conducting elements 36 are secured, and through these elements the current is conducted to the motor 18. An electric light socket may be mounted at the lower end of the suspension tube 21 as indicated at 37 and an electric light 38 mounted therein, and other sockets may be mounted upon the lower wing 3 as indicated at 39 for the mounting of light bulbs 40 upon the wings. These bulbs may be lighted through current conductors 27 and the fan may thus be made to give light as well.
- It will be seen that when the electric motor is started the air currents set up by the fan 20 will be directed backwardly to or between the wings 2 and 3, some of the currents strike the deflecting members 13 and 15 and to be sent downwardly from the fan 20 while the balance of the current impinges upon the rudder 8, thus causing the plane to revolve upon the friction balls 24 and while the fan 20 is in motion this revolving of the plane will continue.
- From the foregoing description it can be readily seen that there has been constructed an unique and novel fan structure, which will be both effective and attractive.
- Having thus described my invention what I claim is:
1. In a hanging fan of the character set forth, a suspension bar a body revolvably supported intermediate its ends, on said bar, a fan structure mounted upon one end of said body, laterally extending elements carried by said body having means for deflecting downwardly a portion of the air currents thrown backwardly by said fan, and means upon the rear of said body, adapted to be acted upon by air currents from said fan, to cause the body to revolve about said bar.
  2. In a hanging revoluble fan of the character set forth, a vertical suspension bar, a body structure having said bar extended therethrough, a pair of bearing separated ball races one secured to the underside of said body and traversed by said bar and the other secured to and about said bar, a fan structure carried by said body, and means attached to said body for deflecting air currents downwardly therefrom and simultaneously causing the body to revolve on said bearings.

In testimony whereof, I affix my signature hereto.

LUIS CILLEP
